UNITED STATES PATENT OFFICE

171,054

TELESCOPIC CIGARETTE BOX

Maison Sachar, New York, N. Y.

Application July 13, 1953, Serial No. 25,926

Term of patent 7 years

(Cl. D85—2)

To all whom it may concern:

Be it known that I, Maison Sachar, have invented a new, original, and ornamental Design for a Telescopic Cigarette Box, of which the following is a specification, reference being had to the accompanying drawing, forming a part hereof.

Fig. 1 is a perspective view of a telescopic cigarette box, showing my new design.

Fig. 2 is a view in front elevation.

Fig. 3 is a view in rear elevation.

Fig. 4 is a view in side elevation.

Fig. 5 is a top plan view.

I claim:

The ornamental design for a telescopic cigarette box, as shown.

MAISON SACHAR.
